UNITED STATES PATENT OFFICE.

JESSE E. CHENETTE, OF ALBANY, NEW YORK.

GARMENT-HANGER.

1,294,048.

Specification of Letters Patent. Patented Feb. 11, 1919.

Application filed May 6, 1918. Serial No. 232,893.

To all whom it may concern:

Be it known that I, JESSE EDWARD CHENETTE, a citizen of the United States, residing at Albany, in the county of Albany and 5 State of New York, have invented certain new and useful Improvements in Garment-Hangers; and I do declare the following to be a full, clear, and exact description of the invention, such as will enable others skilled 10 in the art to which it appertains to make and use the same.

This invention relates to garment hangers, and it relates more particularly to an improved form of portable hanger bar 15 for supporting a plurality of garment hangers of ordinary construction.

One object of this invention is to provide an improved garment hanger which may be easily and instantaneously attached to an ordinary stationary support such as a hook, 20 nail or other similar element;

Another object is to provide a device of this character which is foldable into a substantially straight and narrow mass, for 25 obtaining convenience in packing for transportation;

Another object is to provide a device of this character which consists of few and simple parts, so as to be manufactured at a 30 comparatively low cost.

Other objects and advantages may become apparent to persons who read the following details of description in connection with the accompanying drawings, in which:

35 Figure 1 is a side elevation of my improved hanger attached to a stationary garment-supporting hook of ordinary construction;

Fig. 2 is a top plan view of the device 40 illustrated in Fig. 1, with the addition of several removable garment hangers depending therefrom;

Fig. 3 is a front end elevation of the device shown in Fig. 1;

45 Fig. 4 is a fragmental portion which illustrates a somewhat modified form of the invention; and

Fig. 5 is a fragmental view, partly in section and partly in side elevation, of the form 50 shown in Fig. 4.

Referring to these drawings in detail in which similar reference characters correspond with similar parts throughout the several views, the hook 6 may be of any 55 ordinary construction and is secured to a wall or vertical surface 7. Likewise, the

removable garment hangers 8 may be of any ordinary construction, being provided with hooks or loops 9, by means of which they are supported on a normally horizontal 60 hanger-bar 10. This bar 10 is provided with a shoulder 11 and with a pivot opening through which a pivot 12 extends, said pivot also extending through an end portion of a bar or rigid supporting element 13 which is 65 provided with a shoulder 14. In this form of the device, the pivotally connected end portions are substantially equal in thickness, and are each substantially equal in width with the width of the shoulders 11 and 14, 70 so that the bars 10 and 13 may be swung on the pivot 12 into alinement with one another, and may also be swung into right-angled relation to one another as shown in Fig. 1. When in this right-angled relation, 75 the shoulders 11 and 14 coöperate with the pivot 12 to prevent relative movement of these bars beyond the right-angled position. The bar 10 is provided with an aperture 15 which receives the meeting ends of a wire 80 loop 16 which extends upward and is engageable with the hook 7 or with any similar support so as to support the other elements of the device.

In order that arm 10 may normally stand 85 at right angles to a horizontal line along the wall 7, I provide a bar 17 and secure its middle part to the bar 13 by means of a screw, brad or other pivot 18, and this bar normally rests against the vertical surface 90 7 while extending laterally from the bar 13 so as to form a substantially T-shaped element. This bar 17 is rotatable about the pivot 18 so as to bring it from its right angled relation to the bar 13 into parallel 95 relation with the latter.

From the foregoing disclosure, it will be seen that the shoulders 11 and 14, the pivot 12, the supporting element 16 and the bar 17 mutually coöperate, in connection with the supporting elements 6 and 7, to support the bar 10 in a position at right angles to vertical and horizontal lines which coincide with the surface 7; and it may also be seen that this device may be quickly and conveniently attached to and detached from an ordinary garment hook and folded into a convenient shape for transportation.

In the modified form shown in Figs. 4 and 5, the vertical element 13' is bifurcated for 110 receiving a tongue 10' of a hanger bar 10a. This form is considered somewhat stronger

than the form previously described, but the device formerly described has the advantage of being somewhat simpler.

Although I have shown this device applied to a plane vertical surface, it is to be understood that the same is applicable where the hook 6 is secured on a batten or other connection which overhangs the surface 7, and in this connection, it is not beyond the scope of this invention to position the loop 16 farther from the pivot 12, or to thicken the bar 17 or apply a filler between the same and the surface 7.

Although I have described this embodiment of my invention very specifically, it is to be understood that my invention is not limited to these exact details of construction and arrangement of parts, but I am entitled to make minor changes within the scope of the inventive idea disclosed in the foregoing description and following claims.

What I claim as my invention is:

1. A portable garment hanger comprising a member provided with a shoulder adjacent to one end, an arm provided with a shoulder adjacent to one end, a pivot securing the shouldered end portion of said member to the shouldered end portion of said arm and being coöperative with said shoulders for preventing movement of said arm beyond a

predetermined angle relative to said member, and a loop secured to said arm and being coöperative with said member and with a vertical surface and with a hook or similar support so as to retain said arm in a 35 horizontal position, said arm and member being movable on said pivot with relation to one another so as to aline these pivotally connected members for convenience in packing for transportation. 40

2. A portable garment hanger comprising a bar provided with a shoulder adjacent to one end, a second bar provided with a shoulder adjacent to one end and pivotally secured to the first said bar in such relation 45 that said shoulders coöperate with the pivot to prevent relative movement of these bars beyond a predetermined angle about said pivot, a third bar having its middle portion pivotally secured to one end portion of the 50 first said bar, and a loop secured to the second said bar and engageable with a supporting element so as to support said bars, the first and second said bars being movable on their pivot into alinement, the second and 55 third said bars being movable on their pivot into parallel relation with one another.

In testimony whereof I have hereunto set my hand.

JESSE E. CHENETTE.
